UNITED STATES PATENT OFFICE

NICHOLAS FRESCOTT, SR., OF INWOOD, NEW YORK, ASSIGNOR OF ONE-FOURTH TO
CHARLES JOSEPH SCHWARTZ, OF BROOKLYN, NEW YORK

TRUNK SUPPORTING ATTACHMENT

Application filed October 30, 1931. Serial No. 572,188.

The present invention relates to an attachment for a trunk to support the same so that the trunk may be easily and readily moved from place to place.

5 Another very important object of the invention resides in the provision of an attachment of this nature particularly designed for a wardrobe trunk so that the same may be easily and quickly opened and when desired moved from place to place.

Another very important object of the invention resides in the provision of an attachment of this nature which is exceedingly simple in its construction, inexpensive to manufacture, thoroughly efficient and reliable in use and otherwise well adapted to the purpose for which it is designed.

With the above and numerous other objects in view as will appear as the description 20 proceeds, the invention resides in certain novel features of construction, and in the combination and arrangement of parts as will be hereinafter more fully described and claimed.

25 In the drawings:

Figure 1 is a bottom plan view of the apparatus embodying the features of my invention.

Figure 2 is a side elevation thereof.

30 Figure 3 is a fragmentary longitudinal section through one of the bars.

Figure 4 is a detail section taken substantially on the line 4—4 of Figure 1.

Figure 5 is a section taken substantially 35 on the line 5—5 of Figure 4.

Figure 6 is a sectional view taken substantially on the line 6—6 of Figure 1.

Figure 7 is a bottom plan view of another embodiment of the invention.

40 Figure 8 is an enlarged detail bottom plan view of one of the bars.

Figure 9 is a detail top plan view of one of the diagonal bars, and

Figure 10 is a sectional view taken substantially on the line 10—10 of Figure 9.

Referring to the drawings in detail, it will be seen that numerals 5 denote a pair of bars having claws rising from adjacent ends thereof as shown at 6. The other ends of

50 the bars 5 are formed with sleeves 7 for re-

ceiving bar sections 8 which are longitudinally slotted as at 9. A screw bolt 10 extends through the end of the sleeve 7 and through the slot 9 so that the sleeve may be frictionally tightened on the section 8 to hold it in 55 adjusted position. A pin 11 projects from the section 8 through a slot 12 in the sleeve 7 and is engaged in an arcuate slot 14 in an arcuate member 15 formed on a lever 16 rockable as at 17 under the sleeve 7. By rocking this 60 lever 16, the section 8 may be slid into and out of the sleeve to lengthen or shorten the bar 5. On the outer end of the section 8 there is formed a claw 20. A casting 21 has a ball bearing mounting 22 under the section 65 8 adjacent the claw 20. Numerals 23 denote a pair of diagonal bars, adjacent ends of which are provided with elongated slots 24 to receive set screws or bolts 25 in intermediate portions of the bars 5. On the other 70 end of the diagonal bar 23 are angular claws 26 and under said ends are mounted casters 27 by ball bearing means as previously explained in conjunction with casters 21.

This embodiment of the invention is shown 75 in its preferred use as in Figure 1 under the trunk. It will thus be seen that the wardrobe trunk may be easily opened up by swinging its sections as indicated by the arrows 28.

In Figure 7 I have shown another embodiment of the invention wherein bars 5 have casters 27 mounted under their ends adjacent claws 6 when the apparatus is to be used under an ordinary trunk.

From the above detailed description it will be seen that I have devised an attachment apparatus which may be easily and quickly engaged on trunks of different sizes and will enable the trunks to be easily opened 80 up and to be transported from place to place.

The present embodiments of the invention have been described in considerable detail merely for the purposes of exemplification 85 since in actual practice they attain the features of advantage enumerated as desirable in the statement of the invention and the above description.

It will be apparent that changes in the 100

details of construction, and in the combination and arrangement of parts may be resorted to without departing from the spirit or scope of the invention claimed or sacrificing any of its advantages.

Having thus described my invention, what I claim as new is:

1. In a device of the class described, a bar comprising a pair of telescoping sections, article engaging claws on the free ends of said sections, a caster support for one of said sections, a caster support for the other of said sections including a member arranged diagonally to said other of said sections and connected to an intermediate portion thereof and having a caster secured thereto, and means for adjusting said sections with respect to each other to vary the length of said bar, including a pin on one of said sections and a lever pivoted upon the other section and having an arcuate slot for receiving said pin.
2. A supporting attachment for trunks, comprising two adjustable telescoping bars, trunk engaging claws on the ends of said bars, a caster supporting one of said bars adjacent one end thereof, a third bar, bolt and slot means adjustably connecting one end of the third bar with one of the first-named bars intermediate the ends of the latter, an angular trunk engaging claw on the free end of the third-named bar, and a caster supporting said last-named end of the third-named bar.

35 In testimony whereof I affix my signature.
NICHOLAS FRESCOTT, Sr.
